DESIGN FOR A TRAFFIC SIGNAL

Jeremiah D. Kennelly, Oak Park, Ill., assignor of
one-half to Ethel V. Mars

Application September 10, 1936 Serial No. 64,797

Term of patent 7 years

To all whom it may concern:

Be it known that I, Jeremiah D. Kennelly, a citizen of the United States, residing at Oak Park, in the county of Cook and State of Illinois, have invented a new, original, and ornamental Design for a Traffic Signal, of which the following is a specification, reference being had to the accompanying drawing forming a part thereof, in which:

Figure 1 is a front view in elevation of the traffic signal showing my new design; and Fig. 2, a top plan view.

I claim:

The ornamental design for a traffic signal as shown.

JEREMIAH D. KENNELLY.
